(57) CLAIM

The ornamental design for an earbud holder, as shown and described.

DESCRIPTION

FIG. 1 is a perspective view of an earbud holder showing my new design;

FIG. 2 is a back plan view thereof;

FIG. 3 is a front plan view thereof;

FIG. 4 is a left side view thereof, the right side being identical; and,

FIG. 5 is a top plan view thereof, the bottom plan being identical.

The right side plan view is identical to the left side plan view, and the bottom plan view is identical to the top plan view.
